**SELF-PROPELLED DISPENSING AND SPREADING
UNIT AND COMPACTER**

Ernest L. Carpenter, Comanche, Tex.

Application June 5, 1957, Serial No. 663,737

1 Claim. (Cl. 222—177)

This invention relates to a spreader device, and it particularly relates to a self-propelled spreader for spreading and compacting aggregate during the asphalting of highways and the like.

Hitherto, in asphalting highways, the hot asphalt was first spread completely over the area to be treated before the aggregate was spread thereover in a second operation. Then, after the aggregate was completely spread, the area was rolled to embed the aggregate into the asphalt. One of the great disadvantages of this system was that by the time the area was rolled, the asphalt had almost completely cooled and solidified, making it somewhat difficult to sufficiently embed and adhere the aggregate within the asphalt. The most efficient method would consist of compacting or embedding the aggregate in the asphalt immediately after the asphalt is spread since asphalt is generally spread at high temperatures, usually ranging between about 375° F. to 400° F. Aggregate which is embedded or rolled into the still liquid, hot asphalt would be firmly bonded in place when the asphalt cooled so that there would be little or no "whip-off." The term "whip-off" is commonly used to refer to the loose aggregate particles which are whipped or flung off the highway by moving traffic before they have a chance to become firmly embedded in the asphalt.

Another problem inherent in the systems heretofore in use involved the necessity to halt the movement of the spreader at intervals in order to reload it with aggregate. This caused a great loss of time since many such stops were necessary during the asphalting of a highway or road of any length. Since the time during which the work could be accomplished is already severely limited by weather conditions, the additional loss of time required for reloading of the spreader involved much waste of time and money.

It is one object of the present invention to obviate the above and other difficulties by providing a device which can quickly spread and embed aggregate particles while the asphalt is still hot.

Another object of the present invention is to provide an aggregate spreader which is adapted to operate continuously without any need for stopping to reload.

Another object of the present invention is to provide an aggregate spreader which is capable of evenly metering and spreading the aggregate along its entire width or of distributing the flow of aggregate to any portion of its width as desired.

Other objects of the present invention are to provide an improved spreader device, of the character described, that is easily and economically produced, which is sturdy in construction, and which is highly efficient in operation.

With the above and related objects in view, this invention consists in the details of construction and combination of parts, as will be more fully understood from the following description, when read in conjunction with the accompanying drawings in which:

Fig. 1 is a top perspective view of a spreader device

2

embodying the present invention, the device being shown during use.

Fig. 2 is a top plan view, with parts broken away, of the device of Fig. 1.

Fig. 3 is a side view, partly in elevation and partly in section, of the device of Fig. 1.

Fig. 4 is a bottom view taken on line 4—4 of Fig. 3.

Fig. 5 is a perspective view of the operating feed parts with the corresponding portions of the chassis omitted.

10 Fig. 6 is a view, partly in elevation and partly in section, taken on line 6—6 of Fig. 3.

Fig. 7 is a side elevational view of one of the partitions in the hopper.

Fig. 8 is a sectional view taken on line 8—8 of Fig. 7.

15 Fig. 9 is a fragmentary, enlarged, detailed, sectional view of the feed roller and its associated parts.

Referring now in greater detail to the drawings wherein similar reference characters refer to similar parts, there is shown a spreader device, generally designated 10, which 20 comprises a chassis 12 at the front end of which is provided a hopper 14 defined by an inclined rear wall 16 and a straight front wall 18. A rearwardly and downwardly inclined top wall 20 is provided with a central, rectangular opening covered by a screen 22.

25 At the lower end of the hopper 14 an opening 24 is provided, this opening being defined by an outwardly-arcuately curved, lower rear wall section 26. The front wall 18 ends above the opening 14 and a flexible curtain 28 suitably secured thereto depends therefrom to partly 30 overhang the opening 24. A gate 32 is movably positioned on wall 18 by headed stud 30 through slots 31 to open or close the opening 24. This gate 32 is operated by means of a pair of arms 34 which are connected to a common cross-shaft 36 by links 38. The left hand link 35 is, in turn, connected to a hand lever 40 at the operator's station. This hand lever is used to raise and lower the gate and may be locked either in the closed, the open or any intermediate position by ordinary latching means.

35 Adjacent the opening 24, within the area defined by 40 the curved wall 26, is a metering feed roller 42. This feed roller is divided into a plurality of sections by peripheral slots 44, each section including helically extending spaced apart ribs 46 providing feed pockets 47 therebetween. As best shown in Figs. 3 and 9, the ribs 46 45 coat with the flexible curtain 28 to meter the aggregate dispensed from the hopper so that a predetermined amount is dispensed with each rotation of the feed roller. This is accomplished by the curtain coating with each rib 46 and pocket 47 to flexibly contain an amount of aggregate until the rib passes below the lower end of the curtain, at which time the amount of aggregate in the pocket between that rib and the next rib above falls by gravity through the opening 24.

45 The station for the operator 45 is at the left of the 50 screened opening 22 at the top of the hopper, and includes a seat 48, a vehicle steering wheel 50 and all the various controls necessary for the operation of the device. The device is, itself, a self-contained vehicle wherein the chassis 12 is mounted on a pair of front power wheels 52 and a pair of rear steering wheels 54.

55 Each of the steering wheels is mounted on an individual axle on an individual supporting shaft 55, these axles being connected to corresponding levers 56 by a universal joint 58. The levers 56 are connected by corresponding joints 60 to a cross-shaft 62. This cross-shaft 62 is centrally provided with a joint 64 connecting it to a lever 66. The lever 66 is connected by a joint 68 to a steering shaft, not shown; this shaft being connected, in the ordinary manner, to the steering wheel 50.

60 70 The power wheels 52 are mounted on individual axles upon which are also provided sprockets 70 which are

connected by chains 72 to corresponding drive sprockets 74. Each sprocket 74 is connected by a shaft 76 to a sprocket 78 which is connected by a chain 80 to a sprocket 82 mounted on the shaft of a differential gear system indicated at 84. This differential gear system is of the type ordinarily used in automobiles or trucks to enable the drive wheels to turn corners and is equipped with high and low forward speeds and reverse. The high speed is used for moving the vehicle from one working area to another while the low speed is used to move the spreader behind the asphalt distributor during spreading and rolling operations. The differential gear system is connected to an engine 86.

Connected to the drive shaft of engine 86 is a shaft 87 upon which is mounted a sprocket 88. This sprocket 88 is connected by chain 90 to a sprocket 92 mounted on a shaft 94 to drive this shaft 94. Also mounted on shaft 94 is a sprocket 96 which is connected by chain 98 to a sprocket 100 on a shaft 102. This shaft 102 extends cross-wise of the machine and is provided at each end with a sprocket 104 which is connected by a chain 106 to a corresponding sprocket 108 on one end of a shaft upon which is provided a distributing auger 110. The auger 110 is positioned within the hopper and is provided with throwing blades to distribute the aggregate particles toward both sides of the hopper. The blades on one half of the auger are oppositely inclined relative to the blades on the other half so that the blades on the right side throw the aggregate to the right end of the hopper and the blades on the left side throw it to the left end of the hopper thereby effecting an even distribution.

The auger is provided with peripheral slots similar to those on the feed roller 42 and in corresponding positions. This is to permit the insertion of partition panels 112, such as shown in Figs. 7 and 8, within the hopper. To place these panels into the hopper, the bottom portion 114 is inserted into a peripheral groove or slot 44 on the feed roll and then straightened to engage a corresponding slot on the auger within the half slot 116. This lower portion 114 is then bolted to the sides of the hopper by means of cap screws or the like. Thereafter, the upper portion 118 is put in place with the half slot 120 mating with half slot 116 and this upper portion is also fastened to the sides of the hopper. Flanges, not shown, on each portion, extending laterally from the edges, permit easy fastening. Spring clips 122 are secured to the upper portion 118 and press against the lower portion to maintain the alignment as well as to add to the rigidity of the assembly. The partitions may be inserted between the corresponding slots on the feed roller and auger at any predetermined distance from the center in order to vary the operating width of the hopper depending on the width of the area to be treated.

The feed roller 42 is driven by the power wheels 52 by means of a chain 124 at either end of the feed roller shaft. Each of these chains 124 extends between a sprocket 126 on the feed roller shaft and a sprocket 128 on the corresponding wheel axle. An over-run clutch 130 is provided in conjunction with each sprocket 126 in order to compensate for differences in speeds between the two power wheels, as when turning corners.

Rearwardly of the feed roller is provided a pressure roller system for embedding the aggregate into the asphalt. This pressure roller system depends from the underside of the chassis and comprises a first set of axially-spaced pneumatic tired wheels 132 positioned in line with the forward power wheels 52, as best seen in Fig. 4, and a second set of axially-spaced pneumatic tired wheels 134 positioned between the front and rear wheels 52 and 54. The wheels 132 and 134 are so arranged that each wheel 132 lies between a pair of wheels 134. In this manner, the entire ground surface is covered by the roller system.

The wheels 132 and 134 are separated into pairs with 75

each pair mounted on a separate supporting standard 136 or 138. Each support 136 and 138 is provided at its bottom with a pivotal joint, as at 140 and 142. This pivotal joint connects the support standard to the corresponding axle for each pair of wheels and permits compensation between the wheels whereby one wheel goes up and the other down when they pass over a depression or hill. The support standards are connected to the underside of a support plate 144 which is, in turn, supported by cross-bars 146, and chains 148, the chains 148 acting to flexibly support the plate 144. The support plate 144 and the pressure wheels 132 and 134 depending therefrom are adapted to be adjusted to various desired vertical positions by means of chains 150, best shown in Figs. 3 and 6, which are connected, at their lower ends, to brackets 152 on the plate 144. These chains extend over corresponding sprockets 154 mounted on supports in bars 156. Sockets 158 are provided in each sprocket to releasably receive a corresponding socket portion of a handle 160. This handle can be used on each sprocket in order to wind the sprockets to turn the chains and elevate or lower the plate 144. Fixed to each sprocket is a ratchet 162 which coacts with a pivoted dog 164.

Since this machine is relatively short and since the bulk of its weight is at the front end, a counterweight system is provided at the rear end to prevent tilting forward on a very steep grade. This counterweight system comprises a series of trays 166 on the top of the chassis and containers 168 under the upper surface of the chassis, as best shown in Fig. 3. Weights of various dimensions, according to need, are placed in these trays and containers.

In order to permit a dump truck, such as shown at 170 in Fig. 1, to back up to the device and unload directly into it without either the truck or spreader stopping, a skip 172 is provided at the rear of the machine. The skip has a front funnel section 174 and a rear receiving section 176. The skip is pivoted at its front, funnel end, by means of a rocking shaft 178. At its rear end, the skip is provided with loops 180 through which extends a cable 182. The opposite sides of the cable extend around drums 184 and 186 respectively; these drums being mounted on a shaft 188 mounted on a hoisting derrick frame 190. Cross-braces 192 strengthen the frame. A pulley 194 is mounted on one end of shaft 188 and is connected to a winch 196 by a cable 198. The winch 196 takes its power directly from engine 86 by suitable driving connections, generally indicated at 199, and is used to operate the derrick to pivot the skip to the desired position to receive the aggregate from the dump truck and to funnel it into the hopper 14.

In the funnel portion of the skip, a diverter arm 200 is pivotally connected, as at 202, to the front end of the skip. A handle 204, best shown in Fig. 2, is attached to the central portion of the arm 200 and is available to the operator to permit him to pivot the diverter arm into any desired position to shift more aggregate to any portion of the hopper, as needed.

The operation of the device is obvious from the above description. In general, the spreader 10 is self-propelled to follow the asphalt spreader immediately behind and to dispense the aggregate and roll it into the hot asphalt in a continuous operation. When more aggregate is needed, a dump truck, such as indicated at 170 can back up slowly so as to maintain movement with the spreader and dump its load of aggregate into the up-raised rear end of the skip while the spreader continues to move forward. The skip is then lowered by the winch system into the desired position. If the road is narrow or if only a portion thereof is to be treated, the partitions 114 are inserted to limit the effective hopper area to the desired width.

Although this invention has been described in considerable detail, such description is intended as being illustrative rather than limiting, since the invention may be

variously embodied, and the scope of the invention is to be determined as claimed.

Having thus set forth and disclosed the nature of this invention, what is claimed is:

A self-propelled aggregate dispensing device comprising a chassis, drive means on said chassis, wheels for propelling said chassis, and a hopper on said chassis for dispensing aggregate, said hopper comprising a substantially straight front wall, an inclined rear wall extending from a relatively wide upper end of the hopper to a relatively narrow lower end, substantially straight side walls, said hopper being provided with a rearwardly and downwardly inclined screened inlet opening and said lower end being constructed to form a dispensing chute being defined by an arcuately curved rear wall portion comprising a continuation of said inclined rear wall, the lower end of said straight front wall and the lower end of said arcuately curved rear wall portion defining a front opening, a movable gate for closing said front opening, a flexible curtain connected to the internal surface of the front wall of said hopper above said open front portion and extending into said opening, a feed and metering roller encompassed by said arcuate curved rear wall portion, said roller being provided with helical ribs arranged individually to contact said curtain upon rotation of said roller, a distributing auger in said hopper adjacent the upper end thereof, comprised of rotatable shaft having a plurality of helical blades thereon, said auger being divided into two portions, the blades of the two portions inclining in opposite directions from opposite sides of the center line so as to evenly distribute the aggregate,

said roller and said auger being provided with a plurality of vertically aligned peripheral slots, removable partitions insertable in said hopper between corresponding vertically aligned slots in said roller and auger to adjust the width of said hopper, and means operable by said wheel for rotating said roller and said auger.
